UNITED STATES PATENT OFFICE.

OTTO EICK, OF ST. LOUIS, MISSOURI.

DESIGN FOR A RUBBER BRUSH.

44,437.

Specification for Design.

Patented Aug. 5, 1913.

Application filed March 22, 1913. Serial No. 756,223. Term of patent 14 years.

To all whom it may concern:

Be it known that I, Otto Eick, a citizen of the United States, and a resident of St. Louis, in the State of Missouri, have invented a new, original, and ornamental Design for Rubber Brushes, of which the following is a specification, reference being had to the accompanying drawings, forming part thereof.

In the drawings: Figure 1 is an elevation

of the brush viewed from one side thereof; and Fig. 2 a sectional view, taken on the line 2—2 of Fig. 1.

I claim:

The ornamental design for a rubber brush, as shown.

OTTO EICK.
